CLAIM

The ornamental design for a beverage container label, as shown and described.

DESCRIPTION

FIG. 1 is a front perspective view of a beverage container label showing my new design;

FIG. 2 is a front view of the beverage container label;

FIG. 3 is a rear view of the beverage container label;

FIG. 4 is a right side view of the beverage container label;

FIG. 5 is a left side view of the beverage container label;

FIG. 6 is a top plan view of the beverage container label;

FIG. 7 is a bottom plan view of the beverage container label; and,

FIG. 8 is a rear perspective view of the beverage container label.

The broken lines in the drawing depict portions of the beverage container label that form no part of the claimed design.
